UNITED STATES PATENT OFFICE.

THOMAS HARDIE, OF PHILADELPHIA, PENNSYLVANIA, ASSIGNOR OF TWO-
THIRDS TO ARCHIBALD J. ROBERTSON AND ALFRED C. REX, OF SAME
PLACE.

ARMOR-PLATE.

SPECIFICATION forming part of Letters Patent No. 675,511, dated June 4, 1901.

Application filed October 2, 1900. Serial No. 31,777. (No model.)

To all whom it may concern:

Be it known that I, THOMAS HARDIE, a citizen of the United States, and a resident of the city and county of Philadelphia, in the State 5 of Pennsylvania, have invented certain new and useful Improvements in Armor-Plates, as fully set forth in the following specification.

My invention relates to armor-plates for defensive purposes which are used in the construction of war vessels, and has for its object to furnish an armor-plate which is practically impregnable and one that will not crack or split by the impact of a regulation projectile. Up to this time experience and 10 practice demonstrate that many of the best class of steel plates are unable to resist the terrific impact of the projectile. They split, crack, or are pierced, although the experts in the art have used the best of material and 15 ingenious means of manufacture, and I am convinced that they will continue to split or crack and be pierced by the projectile if some means is not utilized for assisting the plate to resist the shock to the plate which is administered 20 by the projectile. In order to accomplish that purpose, I use a steel casting containing sufficient carbon to admit of proper hardening in the process of casting. I supply the 25 plate with a network of steel tubing throughout nearly its entire area, thus binding it together with these tubes and furnishing a supplementary strength to the plate which could not be obtained in any other way.

Referring to the drawings, Figure 1 is a 30 face view, partly in section, of an armor-plate, showing the steel tubing forming a network and cast in the body of the plate and the ends protruding from the edges of the plate. These

open ends are necessary to allow the air and other matter to escape when casting the plate. 40 Fig. 2 represents the edge of an armor-plate, showing the steel tubes in their respective positions on line 33, Fig. 1. This view also shows the steel tubes a greater distance from the face of the plate than to other side thereof. 45 This network of steel tubes are separated from each other, so as to have a solidity of metal separating them. It is obvious that the armor-plate is lighter in weight than a solid plate of the same dimensions would be, which 50 is a noteworthy advantage, and is at the same time much stronger to resist the impact of a projectile. In fact, it will not split or crack, although it may be possible to pierce it.

In the letters of reference, A is the plate 55 proper. B is a steel tube, which is invisibly inclosed in the plate proper in the process of casting said plate, and C is also a steel tube laid transversely, thus forming the network, as stated. 60

Having thus described my invention, what I claim is—

1. A steel armor-plate for defensive purposes to be used in the construction of war vessels, said plate containing an invisible network 65 of steel tubing, substantially as described.

2. In armor-plates the combination of a steel casting, having inclosed in the body thereof a series of transversely-arranged steel tubes 70 forming a network of said tubes in said plate, substantially as described.

THOMAS HARDIE.
